DESIGN FOR A BICYCLE FRAME

Emil D. Da Ros, New York, N. Y.

Application March 23, 1938, Serial No. 76,042

Term of patent 3½ years

To all whom it may concern:

Be it known that I, Emil D. Da Ros, a citizen of the United States of America, residing at 3354 Colden Avenue, in the city of New York, county of Bronx, and State of New York, have invented a new, original, and ornamental Design for a Bicycle Frame, of which the following is a specification, reference being had to the accompanying drawing, forming part thereof.

Figure 1 is a side elevational view of the bicycle frame showing my new design.

Figure 2 is a plan view thereof.

I claim:

The ornamental design for a bicycle frame, as shown.

EMIL D. DA ROS.
